WILLIAM PRINCE-SMITH AND DAVID WATERHOUSE, OF KEIGHLEY, ENGLAND.

ROLLER OF SPINNING, TWISTING, ROVING, AND ANALOGOUS MACHINES.

Application filed February 9, 1928, Serial No. 253,165, and in Great Britain April 1, 1927.

This invention relates to spinning, twisting, roving and analogous machines, and has particular reference to machines wherein the pressure between the front rollers is effected by spring weighting means so functioning as to draw the upper and the lower front rollers of the machine towards one another. When a machine of this kind as now constructed stops working, it is only possible to release the pressure on the rollers by the lengthy operation (often neglected) of manipulating individually all the separate spring-controlled hanger-bolts on the machine. Unless the weighting pressure is uniformly released there is a danger of causing damage to the leather coverings of the top rollers by the formation of flats thereon, and again there is an unnecessary load or resistance to be overcome when re-starting the machine.

This invention therefore has for its objects, to obviate damage to the rollers when a machine is standing at rest, and to decrease the effort necessary to start or to re-start a machine.

Accordingly, the invention comprises a spinning, twisting, roving or analogous machine of the kind wherein the front rollers are spring weighted by means of hanger bolts co-operating with abutment members in such manner as to apply the weighting pressure by tending to draw the upper roller arbors and the lower roller shafting together, and in order to prevent damage to the rollers when the machine is idle and to ease restarting of the machine, the invention provides devices whereby to release the pressure from all said hanger bolts simultaneously on one side or both sides of a machine.

Along each side of the machine therefore there may be arranged, between each successive pair of upper front rollers a spring-controlled hanger bolt supporting an upper abutment member bearing on the arbor carrying the upper front rollers and at its lower end taking into a lower abutment member affording a seating for a bearing pad interposed between it and the lower front roller shafting.

Each of the aforesaid bearing pads may be formed on its surface adjacent the shafting with inclined grooves adapted to receive semi-solid lubricant, or each pad may be constructed with a well to contain lubricant into which dips a felt pad or other suitable wick

whereby the lubricant is conveyed through one or more apertures in the pad to the shafting supported by it.

Alternatively, instead of interposing a grooved bearing pad between each lower abutment member and the lower front roller shafting two or more anti-friction rollers, whereof the arbors may be mounted in ball bearings if desired, may be carried by each lower abutment member and be drawn into contact with the lower front roller shaft by the spring-controlled hanger bolt.

In order to enable the weighting pressure of all the spring-controlled hanger bolts to be relieved simultaneously, one of the following alternative means may be adopted.

For example, each of the aforesaid bearing pads may, at its underside, be formed integrally with a tubular projection adapted to telescope into a corresponding housing, formed on or carried by each lower abutment member, and having within it a plunger or piston between the upper surface of which and the under surface of the bearing pad a spring is confined; and below said plunger or piston there may be articulated a rocking lever whereof the upper end is formed with a cam which contacts with the underside of said plunger or piston and whereof the opposite or lower end is slotted and engages a pin carried by a longitudinally movable rod adapted to be displaced by screw, worm gear or other known means.

Or, instead of the arrangement just referred to, the spring may be located between the butterfly nut and hooked block on the hanger bolt itself, and the cam at the upper end of the articulated rocking lever may engage a projection depending from the bearing pad; the housing being omitted from the lower abutment member which may be constructed with bearings for an arbor upon which the rocking lever may be mounted.

Alternatively, the bearing pad may be supported by a seating block upon which is mounted pivotally the lower abutment member which may be formed with a downwardly projecting leg opposite to which a similar leg extends from said seating block, and between said two legs there may be accommodated the ball-end of one of a series of arms carried by a continuous shaft and embracing one of a series of eccentrics or cams formed on or borne by said shaft, whereby said ball-ended arm may be caused to move inwardly of the two downwardly projecting

legs which are at an inclination to one another.

The action of either one of the above three alternative mechanisms for simultaneously releasing the pressure on the rollers is such as not to disturb the direction of the force applied to the upper and lower rollers to pressure-weight same.

In addition to the aforesaid means for releasing and restoring the pressure on all the rollers simultaneously, individual pressure adjustment of the hanger bolts can also be effected by means of the usual butterfly or similar nuts carried at the upper ends of 15 the bolts.

The invention will not be described by way of example with reference to the accompanying drawings, in which:—

Figure 1 is a vertical section of a portion of 20 the upper part of a machine frame, showing the invention applied to the upper and its corresponding front roller. Figure 2 is a detail rear view of part of the mechanism of Figure 1.

Figure 3 is a view similar to Figure 1 showing a modified form of the mechanism illustrated therein. Figure 4 is a detail rear view of part of the mechanism of Figure 3.

Figure 5 is also another view similar to 30 Figure 1, and showing a further alternative means for releasing the spring weighting.

1 are the upper front rollers and 2 are the lower front rollers of a spinning frame, the rollers 1 being mounted in pairs on arbors 3 supported by the usual brackets 4, and the rollers 2 being carried by a continuous shaft 5.

Along each side of the machine there is arranged, between each successive pair of upper front rollers 1 a hanger bolt 6 supporting a hook-shaped upper abutment member 7 bearing on the upper front roller arbor 3 and having in Figures 3 and 5 a spring 8 confined between it and a butterfly nut 9 on the screw-threaded upper end of the hanger bolt 6.

The lower end of each hanger bolt 6 is hooked and takes into the eye 10 of a lower abutment member 11 which accommodates a bearing pad 13, of brass or other suitable material, interposed between said abutment member 11 and the lower front roller shafting 5; the tension of the spring 8 being adjusted by the butterfly nut 9 in the usual manner.

In Figures 1 and 2 each bearing pad 13 is formed integrally with a tubular projection 13^a adapted to telescope into a tubular housing 11^a integral with each lower abutment member 11, and within said housing 11^a is located a piston or plunger 11^b between the upper face of which and the bearing pad 13 there is confined a spring 11^c.

The bottom of the housing 11^a is provided with a diametrical aperture through

which there projects the upper end of a rocking lever 15 articulated by a pin 15^a mounted in appropriate bearings transversely of the bottom of housing 11^a, and said rocking lever 15 is formed at its head 70 with a cam 15^b adapted to contact with the lower face of the piston or plunger 11^b.

Each lower abutment member 11 is therefore controlled by an individual actuator mechanism. A forked bracket or the like 75 11^d restrains the housing 11^a from lateral movement.

The outer end of each rocking lever 15 is slotted at 15^c and engages a pin 16^a carried by a longitudinally movable rod 16 80 adapted to be displaced by any suitable means (not shown) when it is desired to actuate the pressure-relieving apparatus, such actuation shifting the rocking lever 15 from the position shown in full lines in Figure 2 into the position shown in dotted lines in the same figure, and the effect being to withdraw the nose of the cam 15^b from contact with the plunger 11^b thereby relieving or reducing the pressure exerted by the 85 spring 11^c upon the bearing pad 13.

Obviously, on each side of the machine there is a rod 16 which is common to the whole series of hanger bolts 6 on that side.

Instead of the above described actuator 95 mechanism, each bearing pad 13 may be formed, as shown in Figures 3 and 4, with a cylindrical depending projection 13^a extending into the apertured and bifurcated end 11^c of the lower abutment member 11 where it is engaged by the cam 15^b; the rocking lever 15 and rod 16 being employed 100 as described already.

Figure 2 illustrates a further alternative construction of pressure relieving mechanism, and in this case each bearing pad 13 is supported by a seating block 17 upon which the lower abutment member 11 is mounted pivotally at 17^a.

From said seating block 17 there extends 110 a downwardly projecting leg 17^b and the lower abutment member 11 is extended at 11^c alongside said leg 17^b which is inclined slightly to the block from which it springs; and between members 11^c and 17^b there is 115 accommodated the ball-end 18^a of one of a series of arms 18 each being formed at its base 18^b to embrace a cam 19 carried by a continuous shaft 20.

The shaft 20 is adapted to be rotated by 120 any suitable means in order to project the ball-end 18^a between members 11^c and 17^b to move the extension 11^c angularly and thereby pull downwardly the hanger bolt 6 when it is desired to relieve the pressure weight- 125 ing.

It will be observed that in all the three constructions illustrated in Figures 1, 3, and 5 the action of the pressure-relieving means does not tend to disturb the direction of the 130

pressure-weighting force applied to the front rollers.

It will also be observed that should any wear occur in the bearing pads the alignment of the lower front roller shafting is not affected thereby, and that by the employment of these pads or their equivalent the bearing area presented to said shafting is considerably increased.

10 What we claim is:—

1. Spring-weighting means for the front rollers of spinning, twisting, roving and analogous machines, including, in combination, upper front rollers, lower front rollers, 15 a series of spring-controlled pressure devices drawing said lower front rollers towards said upper front rollers, a series of actuator mechanisms each of which co-acts with one of said series of spring-controlled pressure 20 devices, and operating means common to said series of actuator mechanisms to cause same to release all said spring-controlled pressure devices simultaneously.

2. Spring-weighting means for the front 25 rollers of spinning, twisting, roving and analogous machines, including, in combination, upper front rollers, lower front rollers, a series of spring-controlled pressure devices drawing said lower front rollers towards 30 said upper front rollers, a series of actuator mechanisms each of which co-acts with one of said series of spring-controlled pressure devices, a longitudinal operating member operatively with each of said series of actuator 35 mechanisms to enable same to release all said spring-controlled pressure devices simultaneously.

3. Spring-weighting means for the front 40 rollers of spinning, twisting, roving and analogous machines, including, in combination, a line of upper front rollers mounted in pairs upon arbors, a series of fixed supports for said arbors, a line of lower front

rollers mounted upon a common shaft, a spring-controlled hanger-bolt bearing on each of said arbors, an abutment member co-operating with each of said arbors, an abutment member cooperating with each of said spring-controlled hanger-bolts to support said lower front roller shaft and to press together mutually opposite lower and upper front rollers, a series of actuator mechanisms each of which co-acts with one of said abutment members, and operating means common to said series of actuator 55 mechanisms to cause same to release simultaneously, the pressure exerted by all said spring-controlled hanger-bolts and said abutment members.

4. Spring-weighting means for the front 60 rollers of spinning, twisting, roving and analogous machines, including, in combination, a line of upper front rollers mounted in pairs upon arbors, a series of fixed supports for said arbors, a line of lower front 65 rollers mounted upon a common shaft, a spring-controlled hanger-bolt bearing on each of said arbors, an abutment member co-operating with each of said spring-controlled hanger-bolts to support said lower 70 front roller shaft and to press together mutually opposite lower and upper front rollers, a series of actuator mechanisms each of which co-acts with one of said abutment members, a longitudinal operating member 75 common to said series of actuator mechanisms, and means connecting said longitudinal operating member actuatorily with each of said abutment members to enable same to release simultaneously, the pressure 80 exerted by all said spring-controlled hanger-bolts and said abutment members.

In testimony whereof they affix their signatures.

WILLIAM PRINCE-SMITH.
DAVID WATERHOUSE.
